UNITED STATES PATENT OFFICE.

JAMES EDWARD KANE, OF HOLYOKE, MASSACHUSETTS.

SHEET-COLORING APPARATUS.

Application filed September 27, 1924. Serial No. 740,277.

To all whom it may concern:

Be it known that I, JAMES E. KANE, a citizen of the United States, residing at Holyoke, in the county of Hampden and State of Massachusetts, have invented certain new and useful Improvements in Sheet-Coloring Apparatus, of which the following is a specification.

The present invention relates to apparatus for applying colors to paper. The object is to provide means whereby designs may be printed thereupon, these designs being easily altered, and utilizing any color or combination of colors desired.

15 In the accompanying drawings:—

Figure 1 is a side elevation of an embodiment of the invention shown in a somewhat diagrammatic manner,

Figure 2 is a top plan view of the same,

20 Figure 3 is a view partly in elevation and partly in section of one of the drums,

Figure 4 is an end elevation showing the drum opened,

25 Figure 5 is a plan view of one of the design sheets,

Figure 6 is a cross sectional view through the drum when closed, and

Figure 7 is a detail perspective view illustrating a portion of the drum frame-30 work.

Figure 8 is a detail sectional view through one of the supply conduits.

In the embodiment disclosed a portion of a suitable endless conveyor band is illustrated at 8, and is adapted to carry the paper or paper sheets in a manner well understood. On opposite sides of this conveyor are suitable standards 9 supporting reservoirs 10 for suitable colors or inks, or one or more may be employed for chemicals which causes a spreading or distributing action of the colors.

45 At one side of each set of standards are rotatable printing drums 11 suitably supported and rotated by any desired mechanism. Each of these drums preferably consists of semi-cylindrical sections. These sections comprise semi-circular ribs 12 and radial arms 13 connecting their terminals. On 50 the ribs is mounted a foraminous semi-cylindrical wall 14. The two sections are hinged together at one side, as shown at 15, and their opposite sides are adapted to be connected by a hook 16 and keeper 17. The 55 free side of one section is provided with a

plurality of pins 18 that are adapted to engage in sockets 19 formed in the corresponding side of the other section. Suitably secured to the central portion of one of the sections is the supporting shaft 20, the opposite section having its arms 13 recessed as illustrated at 21 to receive the shaft. The design for printing consists of a fabric sheet 22 having raised designs, indicated at 23 thereon. This sheet is placed about the two sections and has openings 24 in its terminal portions, which openings are adapted to receive the pins 18, the sheet being long enough to extend around the drum and have its ends inturned as illustrated in Figure 6. 60

Secured to the lower portions of the reservoirs 10 are flexible spreader sheets 25, said sheets being disposed at a rearward inclination, and having their lower free ends resting on the fabric of the drums. Extending 65 from one end of each of the reservoirs 10 is a supply conduit 26 that extends longitudinally above the spreader sheet 25 and is provided with suitable discharge perforations in its under side so as to deliver material 70 from the reservoirs on to said sheets. Controlling valves 27 are located in the conduits at the ends of the reservoirs.

In using the apparatus the drums are provided with fabric sheets having the desired design thereon and the different coloring materials are placed in the reservoirs 10, or one of these reservoirs may be provided with a suitable chemical for spreading the colors on the sheets. It will be 80 evident that as the sheets pass beneath the rollers therefore, the coloring material and chemical distributed from the reservoirs will be applied to the drums and in turn the design will be transferred to the sheets. 85 Different materials may be employed for the purpose of spreading the color, but those known to be effective may be one part of denatured alcohol to twenty parts of water or one part of ammonia to twenty parts of water or one part of acetic acid to twenty parts of water. Whenever it is desired to change the design it is only necessary to open the drums, remove the peripheral fabric in place thereon, and replace it with 90 other sheets having other designs.

From the foregoing it is thought that the construction, operation and many advantages of the herein described invention will be apparent to those skilled in the art with- 105

out further description and it will be understood that various changes in the size, shape, proportion and minor details of construction may be resorted to without departing from the spirit or sacrificing of the advantages of the invention.

What I claim, is:

1. In sheet marking apparatus, the combination with an endless conveyor belt, of 10 a plurality of reservoirs supported above the belt and spaced apart, a pattern carrying drum located below one of the reservoirs and partially therebeneath, a drum located below the other of the reservoirs and delivering material to the same portions of the sheets carried by the belt as is supplied by the first-mentioned drum, certain of said drums being located between adjacent reservoirs, a yielding apron secured to the lower portion of 20 each reservoir and resting on the underlying drum, said apron being of substantially the length of the reservoir and drum, and means for delivering fluid material from each reservoir to and substan-

tially the length of the apron connected thereto.

2. In a sheet marking apparatus, the combination with an endless conveyor belt, of a plurality of reservoirs supported above the belt and spaced apart, a pattern carrying drum located below one of the reservoirs and partially therebeneath, a chemical spreading drum located below the other of the reservoirs and delivering chemicals to the same portions of the sheets carried by the belt as is supplied by the first mentioned drum, certain of said drums being located between adjacent reservoirs, a yielding apron secured to the lower portion of each reservoir and resting on the underlying drum, said apron being of substantially the length of the reservoir and drum, and means for delivering fluid material from each reservoir to and substantially the length of the apron connected thereto.

In testimony whereof I affix my signature.

JAMES EDWARD KANE.
